UNITED STATES PATENT OFFICE.

JOSEPH O. DOBSON, OF MOUNT VERNON, IOWA.

SHADE-ROLLER.

1,131,684.

Specification of Letters Patent. Patented Mar. 16, 1915.

Application filed June 8, 1914. Serial No. 843,793.

To all whom it may concern:

Be it known that I, JOSEPH O. DOBSON, a citizen of the United States, residing at Mount Vernon, in the county of Linn and State of Iowa, have invented a new and useful Shade-Roller, of which the following is a specification.

The present invention appertains to shade rollers, and aims to provide a novel and improved device of that character.

It is the object of the present invention to provide a shade roller possessing novel or unique means for the attachment of the shade thereto.

The present invention also comprehends the provision of a spring actuated shade roller, embodying a peculiar assemblage or arrangement of the shade attaching or anchoring means, and the spring actuating means.

It is also within the scope of the present invention, to provide a shade roller of the nature indicated, which will be of comparatively simple, substantial and inexpensive construction, as well as being simple, convenient, practical, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a cross section of the roller, taken through the spring. Fig. 2 is an end view of the roller, looking toward the pawls, and showing the roller locked. Fig. 3 is a fragmental longitudinal section of the roller, parts being broken away. Fig. 4 is a reduced end view, showing the shade completely unwound.

In carrying out the present invention, the roller 1, as usual, is preferably turned from wood, although it may be otherwise manufactured. The roller 1 is provided with a longitudinal chordal split or cut 2, by means of a saw or other suitable implement, to provide a strip or cleat section 3 of segmental-shaped cross section, and seatable

against the flat side 4 of the body or main portion 5 of the roller. It is evident, at this point, that the roller 1 may be readily split or cut in two, to provide the body portion 5 having the flat side 4, to provide the removable segmental strip or cleat 3, or the roller may be formed of separate parts assembled as illustrated.

The body or main section or portion 5 of the roller is provided with a longitudinal bore 6 extending from one end, the bore 6 being eccentric of the roller, as a whole, and being disposed approximately central of the body or main portion or section 5 of the roller. The bore 6 is disposed midway between the flat side 4 of the main or body section 5 and the opposite side thereof, in order that the section 5 will not be materially weakened by the bore 6.

The shade 7, which is of the usual character, has its upper end seated upon the flat side 4 of the body portion or section 5 of the roller, the upper end of the shade being clamped between the body 5 of the roller and the removable strip or cleat 3, whereby the upper end of the shade will be secured or anchored chordally within the roller. The strip or cleat 3 is secured to the body or main section 5 of the roller by means of brads, nails or other securing members, 8, driven through the strip or cleat 3 either along its edges or along its longitudinal median line, and taking into the body 5 of the roller. The brads or securing members 8 will pierce the end portion of the shade 7, and in being driven home, will securely clamp the upper end of the shade between the sections or parts of the roller.

The spring actuating means for the roller embodies a circular plate or disk 10 secured to one end of the roller, over the mouth or outer end of the bore 6, and a spring shaft or spindle 11 is disposed longitudinally within the bore 6, the inner end of the shaft 10 or spindle 11 being journaled to the body 5 at the inner end and concentric with the bore 6, while the outer end portion of the shaft or spindle 11 is journaled centrally through the plate or cap 10.

The coiled wire spring 12 is disposed within the bore 6 around the shaft or spindle 11, and has its inner end secured or anchored to the inner end portion of the shaft 11, while the outer end of the spring 12 is secured to the end plate or cap 10. The inner end convolutions of the spring 12 are

disposed eccentrically of the roller, while the outer convolutions of the spring are reduced in diameter, the outer end portion of the spring being of spiral form, whereby the outer convolution of the spring will be disposed approximately concentric of the roller, in order that the torsional strain of the spring may be properly communicated to the roller from the shaft or spindle.

- 10 The outer end portion of the shaft or spindle 11 is provided with a collar or ratchet wheel 13, and a tongue or trunnion 14, which is engageable in the slot of an ordinary shade roller fixture or bracket to support the shaft or spindle 11 in a non-rotatable condition.

The collar or ratchet wheel 13 is provided with suitable notches 15 for the engagement of the pawls or dogs 16 pivoted to the plate 20 or disk 10 adjacent its rim, the pawls 16 being arranged to drop into the notches 15 by gravity, and being arranged to be thrown out of engagement with the ratchet wheel 13 by centrifugal force, when the roller is actuated. The notches 15 of the ratchet wheel 13 and the pawls 16 are preferably so arranged, with respect to one another and to the anchored end of the shade, that when the shade has been completely unrolled from 30 the roller, as seen in Fig. 4, neither of the pawls will engage the notches 15 of the ratchet wheel, to enable the roller to readily rotate in a retrograde or reverse direction to wind up the shade. In this manner, the 35 objectionable feature of locking the roller when the shade has been completely unwound, is eliminated, and the movement of the shade is always possible, while a dead lock is at no time possible, there being sufficient downward play of the shade at all 40 times, to permit the rebound of the shade, so as to throw the pawl or pawls out of engagement with the ratchet wheel, when it is desired to roll up the shade.

- 45 It is evident that when the roller is rotated due to the unwinding of the shade, the outer end of the spring 12 being connected to the end plate of the roller, will cause the spring to be wound up, whereby when the 50 roller is released, the roller will be actuated in a retrograde or reverse direction, to wind up the shade thereon as usual. The peculiar construction of the spring 12 is of advantage in connection with the eccentricity 55 of the bore 6, inasmuch as the inner end portion of the spring may be of comparatively large diameter, while the outer end portion of the spring is of relatively small diameter, so as to be concentric with the shaft or spindle 11, to assure of the proper actuation of the roller in winding up the shade.

The attaching or anchoring means for the shade is comparatively simple, but is nevertheless thoroughly practical and efficient,

particularly in connection with the eccentricity of the bore 6, it being observed that the attaching means for the shade does not provide any grooves within the roller or projections thereon, which might interfere with the proper action, such as the winding and unwinding of the shade. The end of the cleat 3 may fit under the rim or flange of the end plate or cap 10 as seen in Fig. 3.

A shade roller constructed in accordance with the present invention will be easy and inexpensive to manufacture, there being no appreciable expense, as over the ordinary spring actuated shade roller.

The present roller is mounted upon the fixtures or brackets in the usual manner, with the trunnion or tongue 14 engaging one of the brackets, while the usual trunnion, (not shown) at the other end of the roller, rotatably engages the other fixture or carrier.

From the foregoing, taken in connection with the drawing, the several advantages and attributes of the present device will be obvious to those familiar with the art, without further description or comment being necessary, it being noted that the objects aimed at have been carried out satisfactorily by the provision of the structure herein disclosed.

Having thus described the invention, what is claimed as new is:—

1. A shade roller comprising a body portion having a flat side, a segmental cleat section coöperating with the flat side of the body portion, the body portion having a longitudinal bore extending from one end and disposed between the flat side and the opposite side, means for securing the cleat section to the body portion for clamping one end of a shade therebetween, a disk secured to the said end of the roller over the mouth of the bore, a spindle disposed within the said bore, the inner end of the spindle being journaled to the body portion at the inner end of the said bore and concentrically with the said bore, and the outer end of the spindle being journaled to the said disk concentrically of the roller, and a coiled spring surrounding the spindle, the inner end of the spring being secured to the spindle and the outer end of the spring being secured to the said disk.

2. A shade roller comprising a body portion having a flat side, a segmental cleat section coöperating with the flat side of the body portion, the body portion having a longitudinal bore extending from one end and disposed midway between the flat side and the opposite side, means for securing the cleat section to the body portion for clamping one end of a shade therebetween, a disk secured to one end of the roller over the mouth of the bore, a spindle disposed within

the bore, the inner end of the spindle being journaled to the body portion at the inner end of the said bore and the outer end of the spindle being journaled centrally through 5 the said disk, a spring connected at one end to the spindle and at its other end to the roller, the spindle having a notched collar upon the exterior of said disk, and pawls pivoted to the disk and coöperable with the said 10 notched collar, the pawls and the flat side of the body portion and cleat section being ar-

ranged to prevent the roller being locked when the shade is completely unwound, as set forth.

In testimony that I claim the foregoing as 15 my own, I have hereto affixed my signature in the presence of two witnesses.

JOSEPH O. DOBSON.
